PUTTEE-SHAPING APPARATUS.

1,230,332.

Specification of Letters Patent. Patented June 19, 1917.

Application filed February 9, 1917. Serial No. 147,594.

To all whom it may concern:

Be it known that I, KALMAN F. SENTIVANY, a subject of the King of Hungary, residing at Hartford, in the county of Hartford and State of Connecticut, have invented 5 a new and useful Improvement in Puttee-Shaping Apparatus, of which the following is a specification.

This invention relates to an apparatus for 10 shaping puttees or leather leggings.

The object of the invention is to provide a simple apparatus which can be easily manipulated by anyone for setting the leather of puttees or leggings so that such articles will conform to and remain in the 15 shape of the limbs of the persons by whom they are to be worn.

The apparatus which embodies this invention has a forming block of the desired shape 20 and that can be readily heated arranged for the convenient application of the leather from which the article is to be made, and has a sectional mold of a corresponding shape that is arranged so that it may be easily 25 placed upon the leather for pressing it to the forming block and quickly opened to permit the free removal of the leather from the forming block after the leather has been set 30 in the desired shape, the edge outline of the mold being of such a shape that it forms the pattern by means of which the leather can be trimmed to final shape before being removed from between the forming block and the mold, and the mold lining being so made 35 that it will score the leather where it is to be stitched, where the straps are to be fastened and where the loop slits are to be cut.

Figure 1 of the accompanying drawings shows a side elevation of the apparatus with 40 a small portion broken away. Fig. 2 shows a section on the plane indicated by the dotted line 2—2 on Fig. 1. Fig. 3 is a view looking at the outside of the flattened mold lining and showing the scoring means.

The apparatus is mounted on a pipe 1 which may be supported by any suitable 45 means and connected with any convenient source of steam supply. The forming block 2, desirably of cast iron, is shaped so that it will give the desired conformation to the puttee or legging which it is desired to make. The block will, of course, vary somewhat in 50 size and shape according to the different sizes and shapes of puttees or leggings to be made and it is loosely mounted on the supporting tube so that it may be moved longi-

tudinally and rotated on the tube as the apparatus is manipulated in use. A section 3 of the tube is made angular and an angular opening is made in one end of the forming 60 block so that when the block is slipped onto the angular portion of the tube the apparatus will remain upright, but when the block is slipped longitudinally off from the angular portion of the tube the apparatus 65 is free to be rotated.

The mold, which is desirably formed of iron, has a back section 4, the inside of which conforms to the back of the forming block, that is, that section of the forming block 70 which shapes the back or that part of the puttee which is to conform to the calf of the leg of the wearer. Hinged to each side of the back section of the mold are two side sections 5 and projecting from the free edges 75 of these mold sections are lugs 6. The ends of the lugs are slotted and to the slotted end of one a clamp screw 7 is pivoted. On the threaded end of the clamp screw is a clamping nut 8. When the clamping screw held 80 by one lug is swung into the slotted end of the opposite lug the clamp nut may be turned up so as to draw the two lugs together and force the two hinged sections of the mold 85 against the forming block. When the nut is loosened and the clamp screw turned out of the slot the hinged sections of the mold will swing out so as to free the mold from the forming block.

The mold is supported by a yoke 9, being 90 held thereto by the press screw 10 and guiding rods 11. The press screw is threaded through the yoke and its lower end is rotatably held in the boss 12 on top of the back section of the mold. The press screw has a 95 handle 13 by means of which it may be rotated. The lower ends of the guiding rods are fixed in the boss and the upper ends extend loosely through the yoke. The yoke at one end is hinged by a pivot 14 to an 100 arm 15 which extends outwardly from the forming block. At the other end the yoke is adapted to be temporarily fastened by a pin 16 to a lug 17 which projects from the forming block. When the pin is removed 105 the yoke may be swung up so as to lift the whole mold up and away from the forming block. A lug 18 is desirably provided on the arm 15 to form a stop which will support the yoke and hold the mold in an up-right position when it is swung away from the forming block. The inside of the mold 110

is preferably lined by a piece of leather 19 which is secured in place by screws 20 and nuts 21.

The yoke is unlocked by withdrawing the 5 fastening pin and the mold swung up. A piece of moistened leather 22 is laid on the forming block and the mold is swung down and the yoke fastened. The back section of the mold is then forced down by turning 10 the press screw so as to press the leather and cause it to closely conform to the back of the forming block. The whole apparatus is then moved bodily lengthwise until it is free from the squared portion of the 15 supporting tube and is turned over until the yoke hangs down. The free edges of the leather to be shaped, which is already clamped by the back portion of the yoke, are brought in against the forming block 20 and the hinged sections of the mold brought together and tightened on the leather by the nut and clamp screw. The apparatus can then be rotated until the yoke is up and moved longitudinally until the forming 25 block is again engaged with the squared portion of the supporting tube. In this condition the apparatus remains until the leather has dried and set in the desired shape. The edges of the leather may be 30 trimmed off by means of a knife which is drawn around the end edges of the mold and along the meeting edges of the mold. This gives the leather the finished shape. A strip of wood 23 may be set into the iron block 35 along the meeting edges of the mold section so that the knife used in trimming the leather will not be dulled. To remove the leather the clamp screw is unfastened so as to release the hinged sections of the mold, 40 and after the fastening pin is withdrawn the yoke and the mold swing up leaving the leather free to be removed. A number of these devices, the same or different sizes and shapes, may be arranged on a bench in a 45 row and by the time all are filled with leather and the molds clamped the one in which the leather was first placed is ready to be opened and the leather removed.

The leather lining 19, which is shown 50 opened out in Fig. 3, has the contour of the finished puttee or legging. In order to mark the leather which is pressed the lining is stitched with heavy thread at various localities in such manner that the thread will 55 form a welt on the inside which will be impressed in the puttee leather and score it when in the mold. This is desirably stitched completely around the edge 24 to provide a trimming, near the top 25 and near the bottom 26 of one meeting edge to show where the ends of the straps are to be attached, and at 27 and 28 to indicate where the leather is to be slitted to form the loops through 60 which the binding straps are passed. By 65 this simple means every puttee shaped in

the apparatus is marked so that it may be quickly and neatly finished.

The invention claimed is;

1. A leather shaping apparatus having a forming block, a mold having a back and side sections with its interior shaped to conform to the exterior of the forming block, means hinging the side sections of the mold to the back section, a frame, a hand rotated screw coöperating with the frame for pressing the back section of the mold against the forming block, and means for drawing the side sections of the mold together and causing them to press against the forming block. 70 75

2. A leather shaping apparatus having a hollow forming block, means for heating the forming block, a sectional mold with its interior shaped to conform to the exterior of the forming block, means hinging the sections of the mold together, two sections of the mold having opposed free longitudinal edges, means for positively forcing a section of the mold against the forming block, and means arranged to link together said free edges of the mold and positively draw the sections against the forming block. 80 85 90

3. A leather shaping apparatus having a forming block, a mold having a back and side sections with its interior shaped to conform to the exterior of the forming block, means hinging the side sections of the mold to the back section, means for pressing the back section of the mold against the forming block, and a screw attached to one side section and carrying a nut adapted to engage the other side section for drawing the side sections of the mold together and causing them to press against the forming block. 95 100

4. A leather forming apparatus having a forming block, a sectional mold with its interior shaped to conform to the exterior of the forming block, means hinging the mold sections together, a yoke carrying the mold, means pivoting one end of the yoke to the forming block, means for temporarily fastening the other end of the yoke to the forming block, means carried by the yoke for pressing one section of the mold against the forming block, and means for drawing the hinged sections of the mold together and causing them to press against the forming block. 105 110 115

5. A leather forming apparatus having a support, a forming block rotatably and longitudinally movable on the support, means for preventing the rotation of the forming block when in one longitudinal position on the support, a sectional mold with its interior shaped to conform to the exterior of the forming block, means for pressing one section of the mold against the forming block, and means for drawing the sections of the mold together and causing them to press against the forming block. 120 125

6. A leather forming apparatus having a 130

- tubular support, a forming block mounted on the support, a sectional mold with its interior shaped to conform to the exterior of the forming block, means hinging the 5 mold sections together, a yoke carrying the mold, means pivoting one end of the yoke to the forming block, means for temporarily fastening the other end of the yoke to the forming block, means carried by the yoke 10 for pressing one section of the mold against the forming block, and means for drawing the hinged sections of the mold together and causing them to press against the forming block.
- 15 7. A leather forming apparatus having a tubular support with an angular section, a forming block having an angular opening therein and movable longitudinally on the support onto and off from the angular section thereof, a sectional mold with its interior shaped to conform to the exterior of the forming block, means for pressing one section of the mold against the forming block, and means for drawing the sections of 20 the mold together and causing them to press against the forming block.
- 25 8. A leather forming apparatus having a forming block, a sectional mold with its interior shaped to conform to the exterior of the forming block, means hinging the mold sections together, a yoke carrying the mold, means pivoting one end of the yoke to the forming block, means for temporarily fastening the other end of the yoke to the forming block, a press screw carried by the yoke 30
- for pressing one section of the mold against the forming block, and a clamp screw and nut for drawing the hinged sections of the mold together and causing them to press against the forming block. 35
9. A leather shaping apparatus having a forming block, a sectional mold with its interior shaped to conform to the exterior of the forming block, means hinging the sections of the mold together, two sections of 40 the mold having free longitudinal edges, means for pressing a section of the mold against the forming block, and means for drawing the sections of the mold together and causing them to press against the forming block, the mold sections being so constructed and shaped that when drawn together about the forming block the end edges and free longitudinal edges of the mold provide the pattern by which the shaped leather 45 may be trimmed to finished outline.
10. A leather shaping apparatus having a forming block, a mold having a back and side sections with its interior shaped to conform to the exterior of the forming block, 50 means hinging the sections of the mold together, means for pressing the back of the mold against the forming block, means for drawing the side sections of the mold together and causing them to press against the 55 forming block, and a lining for the mold, said lining having means for scoring the leather when the mold is closed about the block.
